SIGNORS TO MINNEAPOLIS HEAT REGULATOR COMPANY, OF MINNEAPOLIS, MIN-
NESOTA, A CORPORATION OF MINNESOTA.

ELECTRICALLY-OPERATED BURNER-CONTROLLING APPARATUS.

Application filed August 6, 1925. Serial No. 48,656.

This invention relates to new and useful improvements in electrically operated controlling apparatus particularly adapted for use in connection with such structures as, for instance, liquid fuel burners, to automatically control the operation thereof, and more particularly relates to such an apparatus having means for preventing burner resumption in the event of ignition failure, and which apparatus is also provided with a recycling mechanism cooperating with a control device after temporary power failure, to cause the burner motor to resume normal operation.

Broadly, the object of the invention is to provide an improved electrically operated burner controlling apparatus comprising a burner motor and a control motor adapted to operate a switch to close a circuit to the burner motor for a predetermined interval and thereafter to open it. A safety switch is also provided which is responsive to normal burner operating conditions to maintain a closed circuit to the burner motor, until opened by the control motor, the operation of which may be controlled by remote control by a thermal device such as a thermostat, located in an adjacent room. A recycling mechanism is also provided which is electrically connected to the control motor in such a manner as to automatically cause said motor to complete its starting cycle to start the burner motor after temporary power failure.

The particular object of the invention, therefore, is to provide an improved electrically operated burner controlling apparatus adapted for use to automatically control a burner motor or similar device.

Other objects of the invention will appear from the following description and the accompanying drawings and will be pointed out in the annexed claims.

In the drawings there has been disclosed a structure designed to carry out the various objects of the invention, but it is to be understood that the invention is not confined to the exact features shown as various changes may be made within the scope of the claims which follow.

In the drawings:

Figure 1 is a vertical sectional view on the line 1—1 of Figure 2, showing the general construction of the control motor;

Figure 2 is a plan view of Figure 1, show-

ing the contact fingers and the rotary contact member;

Figure 3 is a cross sectional view on the line 3—3 of Figure 1, showing the means provided for operating the contact member 60 and the motor switch shaft;

Figure 4 is a similar view on the line 4—4 of Figure 1, showing the switch mechanism provided for closing the burner motor circuit;

Figure 5 is an enlarged detail sectional view showing the snap action provided in the construction of the motor switch to cause said switches to instantly break their connection with the stationary contacts upon 70 opening of the switches;

Figure 6 is a sectional view on the line 6—6 of Figure 1 showing the commutator of the motor and the brushes in contact therewith;

Figure 7 is a similar view on the line 7—7 of Figure 1 showing the preferred method of mounting the windings in the motor;

Figure 8 is a sectional view on the line 8—8 of Figure 1 showing the recycling mechanism;

Figures 9, 10, 11 and 12 are diagrammatic views illustrating the various positions assumed by the burner motor switches during 85 a complete cycle of operation of the control motor;

Figure 13 is a wiring diagram showing the parts in "off" position, ready to commence the starting cycle when the movable 90 contact of the thermostat engages the starting contact; and

Figure 14 is a similar view showing the parts in "on" position, or the position assumed when the burner is operating.

In describing the construction and operation of this novel control apparatus and its associated parts such as the recycling mechanism and the burner motor switches, the control motor, including the above mentioned recycling mechanism and motor switches, will first be described in detail, after which the construction of the safety switch and other parts will be described and their operation in conjunction therewith.

The form of control motor here shown comprises a rotor 21 mounted upon a shaft 22 which is rotatably mounted in suitable bearings 23 and 24 provided in a bearing bracket or end-cap 25 and the intermediate

casing wall 26, respectively, are shown in Figure 1. The bearing bracket 25 is suitably secured to the casing 27 by such means as bolts or screws 28, shown in Figures 2 and 6. A commutator 29 is also mounted upon the shaft 22 and is electrically connected to the rotor 21 as is customary in structures of this type. The rotor 21 is concentrically mounted in the stator 31 in spaced relation thereto so as to provide the usual air-gap therebetween, as shown in Figure 7. Field coils or windings 32 are mounted in insulated relation upon the stator 31 to supply energy to the rotor 21. These coils are connected in series and have conductors 33 and 34 leading therefrom to a suitable source of supply, such as the conductors 35 and 36 of the supply circuit, shown in Figures 13 and 14. The rotor 21 and stator 31 are constructed of laminated metal as is customary and well-known in electrical devices of this type.

An important feature in the construction of this novel control motor resides in the provision of a rotatably mounted instrumentality or contact member mounted in the upper portion of the motor casing 27, and which is operatively connected to the rotor shaft 22. This instrumentality or contact member preferably comprises a cylinder 37 having a plurality of contacts 38, 39, 41 and 42 provided thereon, which are adapted to be engaged, respectively, by a like number of flexible contact fingers 43, 44, 45 and 46 (see Figure 2). An annular contact 47 is also provided on the cylinder 37 adapted constantly to be in electrical engagement with a contact finger 48. This finger 48 is mounted upon a terminal post 49 to which one end of a conductor 51 is electrically connected. The other end of this conductor is connected to one of the brushes 52, which is yieldably held in electrical contact with the periphery of the commutator by means of a spring-actuated arm 53. The other brush 52 has a conductor 54 connecting it with the terminal post 55 to which the contact finger 43 is secured (see Figures 1 and 2). The contact fingers 44, 45 and 46 are similarly mounted upon terminal posts 56, 57 and 58. The cylinder or contact member 37 is secured to a shaft 59 which is rotatably mounted in bearings 61 and 62 provided in the bearing brackets or end-caps 25 and 63, the latter being secured to the casing 27 by means of similar bolts 28 as shown in Figure 2.

The means provided for operating the shaft 59 consists of a train of gears mounted within the casing 27 and operatively connecting the reduced end-portion 64 of the motor shaft 22 with the shaft 59 (see Figures 1 and 3). A pinion 65 is mounted upon the reduced end-portion 64 of the rotor shaft 22 and meshes with a gear

66 having a pinion 67 thereon meshing with a similar gear 68, which also has a pinion 69 secured thereto. This pinion meshes with a gear 71 which also has a pinion 72 secured thereto and adapted to mesh with a gear 73 meshing with a pinion 74, as shown by the dotted lines in Figure 3. The pinion 74 is secured to the relatively smaller gear 75 meshing with an intermediate gear 76 which meshes with a similar gear 77 mounted upon the shaft 59 as shown. Thus when the rotor shaft 22 is rotated, the shaft 59 will simultaneously be rotated at a relatively slower speed with the resultant rotation of the contact member 37. Such rotation of the contact member or cylinder 37 will cause the contacts thereon to be moved in and out of electrical connection with the contact fingers as will hereinafter be described.

The control motor above described is of the repulsion type and it is therefore well known to those familiar with the art that to start such a motor it is usually necessary to short circuit the brushes 52, which in this case is accomplished by the contact member 37 operating in connection with a thermal device and a recycling mechanism as will subsequently be described. The thermal device may be such an apparatus as a thermostat located remote from the control motor as, for instance, in an adjacent room, so that temperature variations in the room will cause the thermostat to start the control motor at a predetermined temperature to start the burner motor or to interrupt its operation. This thermostat is diagrammatically shown in Figures 13 and 14, and comprises a thermo bar 78 mounted upon a post 79 and having its flexible end-portion adapted to engage a pair of relatively fixed contacts 81 and 82. The post 79, supporting the thermo bar 78, is electrically connected to the terminal post 55 of the control motor by means of a wire 83, and the stationary contacts 81 and 82 are similarly connected to the posts 56 and 57 of the control motor by wires 84 and 85, respectively (see Figures 13 and 14). The purpose of the thermostat is to effect the starting of the control motor to control the operation of the burner motor when predetermined room temperatures are reached.

The recycling mechanism provided for automatically causing the control motor to complete its starting cycle to start the burner motor after temporary power failure, is shown in Figures 1, 2, 8, 13 and 14. This mechanism comprises a relay coil 86 having one end connected by a wire 87 to the terminal post 58. The other end of the coil 86 has a wire 88 connecting it with one end of a small coil or winding 89 which is inductively connected with the field windings 32 of the control motor so that induced current will flow there-

through when its circuit is closed. The other end of the coil 89 is connected by a wire 91 to the terminal post 49 as shown in Figures 1, 13 and 14. The coil 89 is relatively small in size and may be mounted adjacent one of the field coils 32 as shown in Figures 1 and 7. The relay coil 86 may be suitably supported by means of a bracket 92 secured to the raised portion 93 of the casing 27 as shown in Figures 1 and 2. A movable contact arm 94 having a contact tip 95 thereon is pivotally mounted upon a post 96 mounted in insulated relation upon a plate 97, as shown in Figures 2 and 8 and on which plate the previously described terminal posts 49, 55, 56, 57 and 58 are similarly mounted, so as to prevent short circuiting of the current between the posts. The plate 97 is suitably mounted upon the upper portion of the casing 27 and is secured thereto by means of screws 98. A relatively fixed contact point 99 is also mounted in the plate 97 and is adapted to be engaged by the contact tip 95 on the movable arm 94 when the relay coil 86 is de-energized. This contact point is similarly insulated from the plate 97. The movable arm 94 is electrically connected by a wire 101 to the wire 85 leading from the fixed contact 82 of the thermostat, and the relatively fixed contact 99 is similarly connected by a wire 102 to the wire 83 of the thermostat. The air gap between the movable contact tip 95 and the relatively fixed contact 99 is such that when the two contacts are moved into electrical engagement with each other, as a result of the de-energization of the coil 86 caused by temporary power failure or interruption of the flow of current through the relay circuit, the air gap between the removable arm 94 and the lower portion 103 of the coil 86 will be sufficiently wide to prevent the arm 94 from being attracted by the coil to open the circuit between the contacts 95 and 96 when the relay coil 86 is again energized. Means are, therefore, provided for mechanically raising or lifting the arm 94 so as to bring it into the magnetic field of the coil 86 after which it will be attracted by the coil and raised to the position shown in Figures 8 and 14. Under normal operating conditions the movable arm 94 will be held in the raised position shown in the above mentioned figures.

55 The means provided for mechanically lifting the arm 94 into the magnetic field of the coil 86, preferably consists of a cam 104 mounted upon the cylinder 37, and which is adapted to engage a depending lug 105 secured to the arm 94, thereby to raise it sufficiently to cause it to be attracted by the coil 86 to its inoperative position shown in Figures 8 and 14. The purpose of this recycling mechanism is to provide means for automatically starting the control motor to complete its starting cycle of operation after temporary power failure, should the supply of electrical energy to the control motor accidentally be interrupted during the period when the control motor is in the "on" position and the burner motor is operating as shown in Figure 14. During the "off" position of the control motor, and when the burner motor switches are in open position as shown in Figure 13, the flow of current through the relay coil 86 will be interrupted as a result of the wire 87 leading therefrom to the terminal post 58 being open between the contact 42 and the flexible finger 46. The purpose of thus opening the relay circuit when the control motor is in "off" position is primarily to prevent unnecessary consumption of current during such position or cycle of operation. A cover or closure 100 is preferably provided to cover the recycling mechanism and also the rotary contact member 37 and its complementary contact fingers.

50 The means provided for controlling the flow of current to the burner motor consists of a starting switch 106 and a running switch 107 preferably mounted on an insulating plate 108 within the casing of the control motor, and which switches are operatively connected to the rotor shaft 22 and also to the shaft 59 upon which the contact member 37 is mounted. To differentiate between these two motor switches the former will hereinafter be referred to as the starting switch and the latter as the running switch. The starting switch 106 and the running switch 107 are pivotally connected to a conductor strip 109 having a wire 111 leading therefrom to the conductor 33 connecting the field winding 32 of the control motor with the supply circuit. Thus the two switch arms 106 and 107 are constantly in electrical connection with the supply circuit. Relatively fixed contact blades 112 and 113, preferably flexible, are also mounted upon the insulating plate 108. The starting switch blade 112 has a wire 114 connecting it with the windings of the burner motor 115, and a wire 116 leads from the other end of this winding to the conductor 34 of the control motor. Thus when the switch arm 106 is in electrical connection with the contact 112 as shown in Figure 10, a burner motor circuit will be closed to cause the burner motor to start, which condition will obtain until the switch arm 106 is moved out of electrical engagement with the blade 112, as shown in Figures 12, 13 and 14. A wire 117 leads from the flexible contact blade 113 to a safety switch mechanism which will subsequently be described.

55 The switch arms 106 and 107 are each provided with an anti-friction roller 118 adapted to ride upon a pair of cams 119 and 121, mounted upon a relatively short

shaft 122 as shown particularly in Figure 1. One end of this shaft is borne by a bearing 123 mounted in the insulating plate 108 upon which the switch arms are mounted, and the other end of the shaft is mounted in a bearing 124 provided in the end cap 63. The cam 119 is adapted to actuate the starting switch arm 106 and the cam 121 is adapted to actuate the running switch arm 107. The rollers 118 of the switch arms 106 and 107 are yieldably held against the periphery of the cams 119 and 121 by means of a suitable spring member 125 mounted upon the pivots of the two switch arms and having its ends seated against lugs or hooks 126 as shown in Figure 4. This spring member 125 is adapted to exert a constant force against the switch arms 106 and 107 to tend to move them into open position as shown in Figures 9 and 13. A gear wheel 127 is terminally-mounted upon the shaft 122 and meshes with a similar gear 128 secured to the gear wheel 76 so that when the latter is rotated, the gear 128 will simultaneously be rotated to actuate the cam shaft 122. The cams 119 and 121 are preferably mounted for relative movement upon the cam shaft 122, such movement, however, being limited by means of pins 129 secured to the shaft and having their ends seated in slots 131 provided in the hubs of the two cams as shown in Figure 5. The purpose of thus loosely mounting the cams upon the shaft 122 is to provide a snap action for moving the switch arms out of electrical engagement with the flexible blades 112 and 113. Referring to Figure 5 it will be noted that when the rollers 118 approach the heel 132 of either of the cams as indicated by the dotted lines in the above figure, the action of the spring member 125, tending to force the rollers 118 towards the cam shaft 122, will cause the cams to relatively rotate or advance upon the shaft 122 to the full line position shown in Figure 5, thereby causing the switch arm to be instantly moved out of engagement with its supplementary blade which will prevent the current from arcing between the two contacts during the opening movement of the switch. The cams 119 and 121 are also so constructed and arranged as to properly time the opening and closing of the two switches, during each complete cycle of operation of the control motor.

The form of safety switch employed in connection with this novel burner controlling apparatus is preferably of a type adapted to be actuated by the heat of combustion so that it will be directly responsive to burner conditions to open or close the motor circuit. The form here shown is preferably of the mercury type, comprising a non-conductive tube 133 in which a quantity of mercury or other suitable con-

ductive material 134 is contained. The wire 117 leading from the switch blade 113 has its other end secured to a post 135, and a similar post 136 is connected by a wire 137 to the wire 114, leading from the contact blade 112 to the burner motor 115. The contact posts 135 and 136 inwardly project into the tube 133 so that when the tube is in the position shown in Figure 14, the mercury will engage the ends of both contacts thereby closing a circuit to the motor as follows: from the conductor 33 through the wire 111, conductor strip 109, switch arm 107, contact finger 113, wire 117, post 135, mercury 134, post 136, wire 137; thence through the wire 114, burner motor 115 and the wire 116, back to the conductor 34, thereby completing the running motor circuit. When the tube 133 is oscillated upon its center 138 to the position shown in Figure 13, the mercury will flow to the opposite end of the tube thereby opening the circuit between the contact posts 135 and 136 with the resultant interruption of the burner motor. The tube 133 may be supported by an arm 139 having a tension spring 141 connected thereto which tends normally to hold it against a stop 142 as shown in Figure 13. The oscillation of the tube 133 to open and close the burner motor running circuit, is preferably accomplished by means of the thermal element 143 mounted in such a manner that the heat of combustion may act upon it to move it from its inoperative position, shown in Figure 13, to its operative or circuit-closing position shown in Figure 14. Other forms of safety switches may be employed in place of the mercury switch here shown, it being understood that the form of switch employed must preferably be of a type which will be directly responsive to burner conditions to maintain a closed motor circuit upon normal starting of the burner.

From the foregoing, therefore, it will be noted that this novel control apparatus employs two circuits to control the operation of the burner motor; one circuit functioning only to start the motor, and the other to maintain a closed motor circuit during the period of operation when the control motor is on the "on position," as shown in Figure 14. The control motor also employs a plurality of circuits in its operation. The circuits provided by the wires 83, 84 and 85 of the thermostat function only to initially start the control motor at each cycle of operation, after which a positive running circuit will be provided for the control by the closing of the circuit composed of the wires 51 and 54, the post 55, finger 43, one of the semi-circular contacts 38, contact member 37, annular contact 47, finger 48 and the post 49. The above described circuit will short-circuit the brushes 52 of the control motor and will main-

tain a closed running circuit for the motor to complete each cycle of operation, after the motor has been initially started by the room thermostat having engaged one of the contacts 81 or 82. The circuit provided by the recycling mechanism may also function to initially start the control motor to actuate the motor switches 106 and 107 after temporary power failure.

10 Means are preferably provided for manually starting the control motor to cause it to repeat the starting cycle of operation, should the safety switch fail to close the running circuit to the burner motor as a result of

15 ignition failure, which might be caused by the pilot light or ignition means failing to function when the burner motor starting circuit is closed. Such means preferably consists of a push button 144 having wires 145 and 146 connecting it with the wires 83 and 85, respectively, of the thermostat as shown in Figures 13 and 14. Should the ignition means thus fail to function when the motor switches 106 and 107 are closed during the

20 starting cycle of operation of the control motor, and the control motor reaches the "on position" with the room temperature calling for heat; then, after the faulty ignition means has been remedied, the control motor

25 may be caused to repeat its starting cycle of operation to close the burner motor switches by simply actuating the push button 144. Referring to Figures 13 and 14 it will be noted that the closing of the push button circuit, by actuating the button 144, is equivalent to the thermo bar 78 engaging the fixed contact 82 of the thermostat which circuit must be closed to initially start the control motor to repeat its starting cycle of

30 operation.

Operation.

The operation of this novel burner controlling apparatus may be explained with reference to Figures 13 and 14. Figure 13 illustrates, diagrammatically, the position assumed by the parts when in "off" position and the burner motor is inoperative, and Figure 14 illustrates the parts in "on" position as when the burner motor is functioning. When the parts are in "off" position, as shown in Figure 13, the thermo bar 78 may be either temporarily in contact with the post 82 or be positioned between the contacts 81 and 82, as shown, without having any effect upon the control motor. This will readily be seen when it is noted that the finger 45, connecting the post 82 with the contact member 37, is out of engagement with the contact 41 of the member 37. The thermo bar 78 will remain in contact with the post 82 as long as maximum room temperature is maintained. Upon dropping of the room temperature the thermo bar will leave the contact 82 and will travel towards the

35 post 81 as indicated by the arrow. It will also be noted by reference to Figures 13 and 14 that when the contact member 37 is in either "off" or "on" position, the brush circuit of the control motor will be open as a result of the flexible contact finger 43 being out of engagement with the substantially semi-circular contacts 38 provided upon the rotary contact member 37. The gaps provided between the ends of these two contacts 38 are of sufficient width to cause the finger 43 to be moved out of contact therewith when in the positions shown. When thus positioned the contact finger 44 will be in electrical connection with the contact 39 so that as soon as the thermo bar 78 engages the contact 81, a brush circuit will be completed and closed as follows: from the contact 81 through the wire 84 to the post 56; thence through the flexible finger 44, contact 39, contact member 37, rotary contact 47, through the flexible finger 48 to the terminal post 49; thence through the wire 51 to one of the brushes 52; from the other brush 52 through the wire 54 to the terminal post 55, wire 83, post 79 of the thermostat, through the thermo bar 78 and back to the contact post 81. Such closing of the above described brush circuit will cause the control motor to commence its starting cycle of operation to close the motor switches 106 and 107. Upon the initial movement of the rotary contact member 37, the switch arm 43 will engage one of the semi-circular contacts 38 after which the thermostat will cease to function, as the brush circuit will then be as follows: from the brush 52 through the wire 54 to the terminal post 55; thence through the flexible finger 43 to one of the contacts 38, through the contact member 37, rotary contact 47, finger 48, terminal post 49, through the wire 51 and back to the other brush 52, thereby completing a positive running brush circuit. The control motor will thereafter continue to operate to close the motor switches to start the burner motor regardless of the action of the thermostat. As soon as the control motor has thus been started and the thermostat has been rendered inoperative, the cam 119 will actuate the starting switch arm 106 to close the starting circuit for the burner motor as hereinbefore described. As soon as the burner has thus been initially started, which will result if normal conditions exist, the heat of combustion will affect the thermal element 143 and cause it to engage the arm 139 and move it to the position shown in Figure 14, thereby closing the circuit between the contact posts 135 and 136 of the mercury tube.

40 45 50 55 60 65 70 75 80 85 90 95 100 105 110 115 120 125 130

Before the control motor has completed its starting cycle of operation and also before the switch 106 is opened, the running switch arm 107 is moved into closing position as shown in Figure 11 so that when the starting

switch arm 106 is moved out of engagement with the complementary contact finger 112, a closed circuit will be maintained to the burner motor to cause it to continue operating as long as the contact member 37 to the control motor is in the "on" position, shown in Figure 14, and until interrupted by the action of the thermostat in starting the control motor in its next cycle of operation to stop the burner motor. During the starting cycle of operation of the control motor as above described, the contact 42 will be moved into electrical engagement with the finger 46, thereby causing the coil 86 to become energized and to remain energized as long as the control motor is in the "on" position.

As soon as the burner motor has thus been started and the room temperature begins to rise, the thermo bar 78 will reverse its travel and will leave the contact 81 and move towards the opposite contact 82, as indicated by the arrow in Figure 14. During each cycle of operation of the control motor, the first cycle being to start the burner as above described and the second cycle being to interrupt the burner motor; the contact member 37 will travel one-half revolution so that when it comes to rest at the completion of the starting cycle of operation the contact 44 will be out of electrical connection with the contact member 37 and the similar contact member 45 will be in electrical connection with the contact 41, thereby electrically connecting the contact member 37 with the fixed post 82 of the thermostat.

When the thermo bar 78 engages the contact post 82 the brushes of the control motor will again be short-circuited to initially start the motor, and the closed brush circuit will be as follows: from the contact 82 through the wire 85, post 57, finger 45, contact 41, member 37, rotary contact 47, finger 48, post 49, wire 51 to one of the brushes 52; from the other brush 52 through the wire 54, post 55, wire 83 to the post 79 of the thermostat; thence through the thermo bar 78 and back to the post 82. Such closing of the above described brush circuit to the control motor will cause said motor to be initially started, after which the contact finger 43 will again engage one of the semi-circular contacts 38 which will again cause the thermostat to cease its functioning while the control motor is completing its next cycle of operation to stop the burner.

The cam 121 is so designed as to cause the running switch arm 107 to be moved out of electrical connection with its complementary blade 113 a predetermined interval after the control motor has commenced its closing cycle of operation. When the two switch arms 106 and 107 have thus been moved into circuit-opening position, as shown in Figures 9 and 13, the burner motor will be interrupted and the control motor will continue op-

erating until the contact member 37 assumes its normal "off" position as shown in Figure 13.

During the normal operation of the burner motor, and when the rotary contact member 37 of the control motor is in the "on" position, as shown in Figure 14, current will flow through the relay coil 86, thereby causing the movable switch arm 24 to be held in circuit-opening position as shown in Figure 14. It is to be understood that the cam 104 is so arranged with relation to the lug 105 upon the contact arm 94, that the arm 94 will be moved into the magnetic field of the coil 86 about the time that the contact 42 is moved into electrical connection with the contact finger 46, so that when the contact is made the arm 94 will be attracted by the coil 86 and will thereby be held in the position shown in Figure 14.

An important feature of this invention resides in the operation of the recycling mechanism which functions in the event of temporary power failure while the contact member 37 is in the "on" position, shown in Figure 14, and when the burner motor is operating. In the event of such power failure the relay coil 86 will become de-energized allowing the contact arm 94 to be moved into electrical connection with the contact 99 thereby closing a brush circuit which will be as follows: from the contact 99 through the wire 102, wire 83, post 55, wire 54, brushes 52, wire 51, post 49, finger 48, contact 47, member 37, contact 41, finger 45, post 57, wires 85 and 101, post 96 and through the movable contact arm 94 back to the post 99. Thus when power is again applied to the apparatus the control motor will immediately commence its closing cycle of operation and will continue until it reaches its "off" position shown in Figure 13. Should the room thermostat still be calling for heat or be in electrical contact with the contact 81, then the control motor will go through its next cycle of operation to start the burner until it reaches the "on" position, shown in Figure 14, in which position it will remain until again started by the thermostat as a result of the thermo bar engaging the contact bar 82 after the predetermined room temperature is reached. The recycling mechanism, therefore, provides a means for automatically closing a circuit between the thermostat wires 83 and 85 to cause the control motor to repeat its starting cycle of operation after temporary power failure, and when the contact member 37 of the control motor is in the "on" position and the burned motor is functioning.

The safety switch providing for maintaining a closed burner motor circuit during the normal operation of the burner also performs an important function in the operation of this novel apparatus. The primary

purpose of this safety switch is to prevent the burner motor from functioning in the event of ignition failure such as might occur as a result of faulty ignition means, or in case the fuel supply line should become temporarily interrupted and thereafter opened while the burner motor is operating.

It will also be impossible to cause the burner motor to continue functioning if ignition fails to come on upon such initial starting of the burner. This will readily be understood by referring to Figures 13 and 14. In Figure 13 the safety switch is shown in circuit-opening position, the position assumed when the burner is cool or when there is no combustion. In Figure 14 the switch is shown in the position assumed when combustion has taken place and the heat of combustion has caused the thermal element 143

20 to warp and oscillate the mercury tube 133 from the position shown in Figure 13 to the circuit-closing position shown in Figure 14. In the event of temporary power failure and immediate resumption of power thereafter, 25 the burner motor may be immediately started upon the resumption of such power, if the interval of such power failure has not been long enough to cause the thermal element 143 to cool sufficiently to cause the

30 running circuit to the burner motor to be opened. Should the interval of power interruption, however, be long enough to allow the thermal element 143 to cool sufficiently to open the running circuit, then the burner 35 motor will be interrupted and will remain inoperative until the control motor has completed its next starting cycle of operation.

Having thus described our invention what we claim as new and desire to secure by 40 United States Letters Patent is:

1. In an electrically operated burner controlling apparatus, the combination of a burner motor, a control motor for the burner motor, a switch operable by the control motor to close a circuit to the burner motor for a predetermined interval and thereafter to open the same, and a safety switch independent of the control motor circuit responsive to normal burner conditions to maintain a 50 closed burner motor circuit.

2. In an electrically operated burner controlling apparatus, the combination of a burner motor, a control motor for the burner motor, a switch operable by the control motor to close a circuit to the burner motor for a predetermined interval and thereafter to open the same, and a safety switch responsive to normal burner conditions to maintain a closed burner motor circuit, and a recycling mechanism operable after temporary failure of electrical supply during normal running operation of the apparatus to cause said first-mentioned switch to repeat its function.

3. In an electrically operated burner controlling apparatus, the combination of a

burner motor, a control motor for the burner motor, an automatically operable control to start the control motor, means operable by the control motor to render the automatic control inoperative after starting of the control motor and to stop the control motor after a predetermined travel, a switch operable upon said travel of the control motor to close a circuit to the burner motor after a predetermined interval and thereafter to open the same, and a safety switch independent of the control motor circuit responsive to normally operating burner conditions to maintain a closed burner motor circuit.

4. In an electrically operated burner controlling apparatus, the combination of a burner motor, a control motor therefor, an automatically operable control to start the control motor, an instrumentality operable by the control motor, means on said instrumentality to render the automatic control inoperative after starting of the control motor, means on said instrumentality to limit the travel of the control motor, a switch operable upon said travel of the control motor to close a circuit to the burner motor for a predetermined interval and thereafter to open the same, and a safety switch independent of the control motor circuit responsive to normally operating burner conditions to maintain a closed burner motor circuit.

5. In an electrically operated burner controlling apparatus, the combination with a burner motor, a control motor therefor, an automatically operable control to start the control motor, an instrumentality operated by the control motor, means on said instrumentality to render the automatic control inoperative after starting of the control motor, means also on said instrumentality to limit the travel of the control motor, a switch operable upon said travel of the control motor to close its circuits to the burner motor for a predetermined interval and thereafter to open the same, a safety switch responsive to normally operating burner conditions to maintain a closed burner motor circuit, and a recycling mechanism cooperating with said instrumentality after temporary failure of electrical supply during normal running operation of the apparatus to cause said first-mentioned switch to repeat its function.

6. In an electrically operated burner controlling apparatus, the combination of a burner motor, a control motor therefor, an automatically operable control to start the control motor, an instrumentality operable by the control motor and comprising a plurality of contacts adapted to be electrically connected to the automatic control to render said control inoperative after starting of the control motor, and a recycling mechanism also electrically connected with said auto-

- matic control and said instrumentality and operable after temporary power failure during normal running operation of the apparatus, to cause said control motor to complete its cycle of operation to start the burner motor.
7. In an electrically operated burner controlling apparatus, the combination of a burner motor, a control motor therefor, a switch operable by the control motor to close a circuit to the burner motor for a predetermined interval and thereafter to open the same, a thermostatically operable control device to start the control motor, an instrumentality operable by the control motor to render the thermostatic device inoperative after starting of the control motor, a recycling mechanism operable after temporary power failure during normal running operation of the apparatus to cause said control motor to complete its cycle of operation to start the burner, said recycling mechanism comprising a coil arranged in inductive relation to the supply circuit, and having a movable contact adapted to close a supplementary circuit to start the control motor.
8. In an electrically operated burner controlling apparatus comprising in combination a burner motor, a control motor therefor, starting and running circuits for the burner motor, a switch mechanism operable by the control motor to close the starting circuit and to open the same a predetermined interval thereafter, a safety switch in the running circuit responsive to normally operating burner conditions to close said circuit, and a thermostatically operable device cooperating with the control motor to open said burner motor running circuit when a predetermined room temperature is reached.
9. An electrically operated burner controlling apparatus comprising in combination a burner motor and a control motor therefor, starting and running circuits for the burner motor, a switch mechanism operable by the control motor to close the starting circuit, a safety switch responsive to normally operating burner conditions to close the running circuit, a thermostatic device responsive to room temperatures to start the control motor to actuate said switch mechanism, a rotary contact member on the control member having an electrical connection with said thermostatic device, and means on said contact member to provide a positive running circuit for the control motor a predetermined interval after starting regardless of the action of the thermostatic device.
10. An electrically operated controlling apparatus including a control motor, an armature in said motor having a pair of brushes constantly in electrical connection therewith, a winding for supplying electrical energy to said armature having a connection with a source of supply, a rotary contact member having a plurality of contacts thereon adapted to be moved into electrical engagement with a plurality of flexible contact fingers, a thermostat having electrical connections with said rotary contact member and functioning to short-circuit the brushes to initially start said control motor, and means on said contact member adapted to short-circuit said brushes and to provide a positive running circuit for the control motor a predetermined interval after having been started by said thermostat.
11. An electrically operated controlling apparatus including a control motor having an armature mounted therein, a pair of brushes in electrical connection with said armature and adapted to be short-circuited to start the motor, a contact member rotatably mounted in said motor, a plurality of contacts on the member, contact fingers adapted to be engaged by said contacts, one of said contacts being constantly in electrical connection with one of said brushes, and another of said contacts being adapted to maintain a closed brush circuit to cause said motor to continue to operate after having been initially started and thereafter to interrupt the same, and means responsive to temperature changes adapted automatically to initially start said motor.
12. An electrically operated controlling apparatus including a control motor having an armature mounted therein, a pair of brushes in electrical connection with said armature and adapted to be short-circuited to start the motor, a contact member rotatably mounted in said motor, a plurality of contacts on the member, contact fingers adapted to be engaged by said contacts, one of said contacts being constantly in electrical connection with one of said brushes, and another of said contacts being adapted to maintain a closed brush circuit to cause said motor to continue to operate after having been initially started and thereafter to interrupt the same, means responsive to temperature changes adapted automatically to initially start said motor, and a re-cycling mechanism adapted automatically to function after temporary power failure to cause said control motor to repeat its operation.
- In witness whereof, we have hereunto set our hands this third day of August 1925.

HAROLD W. SWEATT.
FREDERICK S. DENISON.

DISCLAIMER

1,605,299.—*Harold W. Sweatt and Frederick S. Denison*, Minneapolis, Minn. ELECTRICALLY-OPERATED BURNER-CONTROLLING APPARATUS. Patent dated November 2, 1926. Disclaimer filed August 28, 1931, by the assignee, *Minneapolis-Honeywell Regulator Company*.

Hereby enters this disclaimer to that part of the claim in said specification which is in the following words:

“6. In an electrically operated burner controlling apparatus, the combination of a burner motor, a control motor therefor, an automatically operable control to start the control motor, an instrumentality operable by the control motor and comprising a plurality of contacts adapted to be electrically connected to the automatic control to render said control inoperative after starting of the control motor, and a recycling mechanism also electrically connected with said automatic control and said instrumentality and operable after temporary power failure during normal running operation of the apparatus, to cause said control motor to complete its cycle of operation to start the burner motor.”
